UNITED STATES PATENT OFFICE.

CURT KUENTZEL, OF AKRON, OHIO, ASSIGNOR TO THE GOODYEAR TIRE AND RUBBER COMPANY, OF AKRON, OHIO, A CORPORATION OF OHIO.

WRAPPING AND UNWRAPPING MACHINE.

1,079,601.

Specification of Letters Patent.

Patented Nov. 25, 1913.

Application filed October 31, 1912. Serial No. 728,856.

To all whom it may concern:

Be it known that I, CURT KUENTZEL, subject of William II, Emperor of Germany, residing at Akron, in the county of Summit and State of Ohio, have invented new and useful Improvements in Wrapping and Unwrapping Machines, of which the following is a specification.

This invention relates to machines for wrapping and unwrapping a strip of material about either a continuous object such as a cable or an annular article such as a tire or tire shoe.

The machine is especially adapted for wrapping and unwrapping tires before and after the vulcanizing process, for wrapping and unwrapping tires for shipping purposes; also for covering and uncovering wires and cables with paper, tape and cloth; finally for wrapping and unwrapping goods which are spooled in coils; such as wires and cables, hose, etc.

The ability of the machine for unwrapping wrapping material from the goods allows the spooling up of the wrapping material on spools, and hence, this material can be used again for wrapping other goods without any extra spooling.

The primary object of this invention is to provide a new and improved machine for carrying out the foregoing objects and to so construct the device that it is capable of wrapping a strip of material about either a continuous or an annular object while revolving in one direction, and also capable of unwrapping the strip of material from the object, provision being made for holding the bobbin against rotation on its own axis while being revolved about the object during the unwrapping operation and constructed that the bobbin may be rotated on its own axis during the placement of the strip of material on the object.

With the foregoing and other objects in view, the invention consists in the novel construction, combination and arrangement of parts constituting the invention to be hereinafter specifically described and illustrated in the accompanying drawings which form a part hereof wherein is shown the preferred embodiment of the invention but it is to be understood that changes, variations and modifications can be resorted to which come within the scope of the claims hereunto appended.

In the drawings in which similar reference numerals indicate like parts in the different figures, Figure 1, is a view in front elevation of the machine embodying this invention; Fig. 2, is a plan view with certain portions of the mechanism omitted; Fig. 3, is a view in side elevation on a reduced scale of the winding mechanism; Fig. 4, is a view in side elevation looking from the right in Fig. 1; Fig. 5, is a view in front elevation of a part of the rotary shuttles employed; Fig. 6, is a view in side elevation of the mechanism shown in Fig. 5 looking from the right thereof to which is added in section the bobbin for carrying the supply of material; and, Figs. 7 and 8 are details of mechanism employed.

For convenience of description of the construction of the mechanism shown in the accompanying drawings, the instrumentalities composing the machine will be grouped and will be described in their grouped relation. Thus, for instance, the mechanism for rotating an annular tire or tire-shoe to receive the supply of material will be described under the general heading of feeding mechanism and the description of the mechanism for applying to or removing a strip of material from the tire or other object will be described under the general heading of winding mechanism.

Feeding mechanism.—The supporting means for the feeding mechanism embodies a pair of upright standards 1 and 2 spaced from each other and with bases 3, and alined heads or table-forming portions 4. The standards 1 and 2 are preferably provided with lateral walls 5 (see Fig. 4). Extending between the bases 3 and the heads 4 of the two standards 1 and 2 are four upright posts 5' constituting guides on which is adapted to reciprocate vertically a carriage 6. The four guides 5' are arranged in pairs forming the corners of an imaginary square. The carriage 6 is provided at alternate corners with outwardly-extending lugs 7 provided with vertically-arranged threaded apertures therein through which extend elevating screws 8 and 9 mounted at their upper and lower ends in the heads 4 and bases 3, respectively, of the standards 1 and 2. The screw 8 is provided at its upper end with a hand wheel 9' for the purpose of affording easy means of manipulation thereof, and each of the screws 8 and 9 bear near

their lower ends sprocket-wheels 10 to receive a sprocket-chain 11 whereby a simultaneous rotation of the two screws is obtained. The carriage 6 is provided with 5 two side integral members 12 provided with apertures constituting bearings for horizontal parallel shafts 13, one only of which is shown in Fig. 1. These shafts are separated from each other a suitable distance 10 and each shaft bears a roller 14 on which the tread portion of a tire 15 is adapted to be revolved. Extending between the side members 12 of the carriage 6 is a rotatable shaft 16 (see Fig. 2) bearing at one end a 15 hand-wheel 17 by which it is rotated. This shaft 16 is reversely-threaded and is adapted to carry a pair of supports 18 on which are mounted upright horizontally-rotating 20 guide rollers 19 adapted to hold the tire 15 in position during its revolution.

In order to rotate the rollers 14 for revolving the tire 15 the following mechanism is employed: Rotatably mounted in the standard 2 is a driving shaft 20 provided 25 with a clutch 21 which is thrown into and out of clutching relation through the medium of a lever 22. The shaft 20 bears a worm 23 (see Fig. 1) adapted to mesh with a worm wheel 24, (see Fig. 4), mounted on 30 a shaft 25 (see Fig. 1) supported in bearings 26. Mounted on the shaft 25 is a sprocket-wheel 27 which receives a sprocket-chain 28 adapted to extend around a sprocket-wheel 29 mounted on a shaft 30 35 supported in bearings 31 on the right outer face of the side wall 5 of the standard 2. Mounted on the shaft 30 is a cone-pulley 32. Rotatably mounted in suitable bearings 33 on the side wall 5 of the standard 2 is a horizontal shaft 34 which bears a cone-pulley 35. A belt 36 extends between and communicates motion from the cone-pulley 32 to the cone-pulley 35 and drives the shaft 34. Mounted in suitable bearings 37 on the 40 wall 5 is a rotatable, threaded shaft 38 and which bears a manipulating or hand-wheel 39 and also a flanged roller 40 which engages the belt 36 and constitutes a belt-shifter for changing the speed of the motion 45 transmitted from the cone-pulley 32 to the cone-pulley 35.

Mounted on the shaft 34 is a worm 41. Extending between the base 3 and the head 4 of the standard 2 is a splined rotatable 50 shaft 42, (see Figs. 1 and 4) fixedly secured to the upper end of which beneath the head 4 is a worm wheel 43 adapted to intermesh with the worm 41 so that motion is thereby transmitted to the shaft 42. Mounted on the 55 splined portion of the shaft 42 is a beveled gear 44 adapted to intermesh with a beveled gear 45 on the shaft 13 of one of the rollers 14. Both of the shafts 13 bear sprocket-wheels 46 (see Fig. 1) between 60 which extends a sprocket-chain 47, (see Fig. 65

2) so that motion is simultaneously communicated to both of said rollers.

From the foregoing, it will be seen that when a tire, or tire-shoe, for instance, is mounted on the peripheries of the two rollers 14 and motion is communicated through the medium of the clutch 21 to the driving-shaft 20, motion will be transmitted through the hereinbefore-described mechanism to these rollers for continuously revolving the 75 tire or tire-shoe 15 and which is guided in its revolution through the medium of the guide rollers 19.

Winding mechanism.—The mechanism for winding or unwinding a strip of material about the tire or tire-shoe during its revolution on the rollers 14 embodies the following mechanism: Mounted on the upper faces of the heads 4 of the standards 1 and 2, is a frame 50 which is roughly described as somewhat in the shape of a horse-shoe with the open side or heel portions of the horse-shoe resting upon the heads 4. Rotatably secured to the front face (in Fig. 1) of the frame 50 are a plurality of flanged 80 rollers 51, and revolvably-mounted on the peripheries of these rollers 51 is a broken ring or annulus, the opening therein being approximately the same as the distance between the two separate portions of the frame 85 50. Also rotatably secured to the front face of the frame 50 are a second series of flanged rollers 53 with the flanges reversely-arranged with respect to the flanges of the rollers 51 and revolvably mounted on the peripheries of the rollers 53 is a second broken annulus 54, the ends of which are separated in the same manner and approximately the same distance as are the ends of the annulus 52. In practice, I customarily employ 90 five rollers 53 so as to suitably support the annulus 54 throughout a complete revolution. The annuli 52 and 54 are eccentrically disposed with reference to each other, that is to say, the axis of revolution of the 95 annulus 52 will be, say for instance, at 56, while the axis of revolution of the annulus 54 will be at 55. The annuli 52 and 54 are provided with pins on which are pivotally mounted links 57 for connecting them together whereby they both revolve, but on 100 different axes of revolution.

In order to revolve the annuli the following mechanism is employed: Mounted in a suitable bearing in the frame 50 is a shaft 105 58 on the rear end of which is a sprocket wheel 59 (see Fig. 2) which is adapted to receive a sprocket chain 60 the opposite end of which is arranged to run on a sprocket wheel 61 on the shaft 25. Mounted on the 110 front end of the shaft 58 is a pulley 62. Mounted on the opposite side of the frame 50 is a shaft 63 on which is an idle pulley 64. Mounted on the outer portions of the frame 50 are other idler pulleys 65, 66, 67 115 120 125 130 135

and 68, (see Fig. 3) approximately polygonally positioned. In order to transmit motion to the annuli from the pulley 62, a belt 69 is employed which is carried around the pulley 62 and from thence over the outer face of the annulus 54 to the idler pulley 64 and from thence around the idler pulleys 68, 67, 66 and 65 and back to the pulley 62. In order to maintain this belt at the proper tension at all times a tension device 70 of any ordinary construction, is employed. The operation of the foregoing mechanism it is thought will be apparent from the description, but for clearness it is amplified as follows: Motion is communicated from the shaft 25 through the sprocket-chain 60 to the shaft 58 and from thence by means of the belt 69 to the shaft 58 and from thence by means of the belt 69 to the annulus 54 which as it revolves causes a simultaneous, but eccentric revolution of the annulus 52.

Bobbin mechanism.—Reference is here directed to Figs. 4, 5 and 6. In the upper portion of the annulus 52, as the parts are arranged in the drawings, is an aperture in which is pivotally mounted a wrist pin 71 of a link 72 the upper end of which is provided with an aperture in which is positioned the head 73 of a shaft 74. The shaft 74 is freely mounted in a suitable bearing in the upper portion of the annulus 54. The link 72 is provided with an aperture to receive the head 73 and extending from said aperture is an opening 100 which is also provided with a parallel groove 101, the opening 100 communicating with the aperture in the link 72 which receives the head 73. The lower portion of the opening 100 is provided with an enlargement 102. A locking pin 75 is provided and arranged to be inserted in the opening 100 and extended into a suitable aperture 103 (see Fig. 7) in the head 73 for locking the member 74 against independent rotation. The pin 75 is provided with a laterally-projecting lug 104 adapted to be passed through the longitudinal groove 101 and when given a partial rotation to lock itself within the enlarged opening 102 against withdrawal and in order to withdraw the pin when desired and when the lug 104 is in registering relation with the longitudinal groove 101 a resilient element such as a spring 106 is provided. The forward end of the shaft 74 is provided with a pair of ears 76 in which is mounted a pin to constitute a hinge for a bobbin-shaft 77, which is thereby pivotally mounted thereon. Mounted on the bobbin shaft 77 is a sleeve 78 held in position by some means such for instance as a washer and a nut on the end of the shaft 77. Slidably mounted on the sleeve 78 is a bobbin 79 which is held in an adjusted position by means of a collar 80. Between the ears 76 and the rear

face of the bobbin 79 is a tension spring 81 which is arranged to resist rotation of the bobbin and the tension of which can be adjusted by shifting the bobbin away from the spring and securing it through the medium of the adjustable collar 80.

In operation, if it is desired to wind a strip on a tire 15, or on a cable extended centrally through the space inclosed by the frame 50 the pin 75 is raised sufficiently to disconnect the crank 72 from the head 73 of the bobbin shaft leaving the bobbin free to revolve as the strip of material is unwound therefrom while the bobbin is moving orbitally about the tire 15 and of course, the degree of tension which is placed on the strip of material during its placement will be determined by means of the tension-spring 81. If it is desired to unwind or remove a strip of material from a tire or any object arranged axially of the opening in the frame 50, the pin 75 is forced inwardly so as to interlock the link 72 and the head 73 of the bobbin-shaft 74, which holds the bobbin fixed against independent rotation during its revolution about the tire and as it moves orbitally about the tire it will wind or take up a strip of material from the tire during its travel.

It will be obvious that a plurality of bobbins may be employed instead of one, and that as the single bobbin moves orbitally about the tire with the pin 75 in the position shown in Fig. 5, the rotation of the bobbin is prevented and the relative position of the various parts thereof will always remain the same, thereby enabling the bobbin to wind up a strip of material as it revolves about the tire.

As tires with their inclosed cores are exceedingly heavy, provision is made for a loading and unloading platform which can be shifted in unison with the carriage 6 and in order to accomplish this loading and unloading of the tires the front and rear faces of the carriage 6 are provided with eyes 82 into which hooks 83 of platforms 84 are engaged for raising and lowering them in unison with the carriage 6. The outer or extended ends of the platforms 84 are provided with rollers 85 to permit them to shift their position in unison with the changes of position of the inner ends of the platforms.

When it is desired to wind a strip of material on an object, one end of the strip is loosened from the spool of material on the bobbin and attached to the tire and the shuttle composed of the two broken annuli are moved about the object as the latter is fed through the space inclosed by the frame 50. In doing this, a proper degree of tension is imposed on the bobbin by means of the spring 81 and its free rotation is thereby braked.

If it is desired to unwind a strip of ma:

material from an object, the end of the strip is unwound from the object and carried to the bobbin and previous to the orbital movement of the bobbin on the shuttle the lock-pin 75 is moved to its operative position, thereby preventing the independent rotation of the bobbin shaft, and if necessary, the tension produced by the spring 81 is increased sufficiently to prevent independent rotation of the bobbin itself. As the spool moves orbitally about the object and is itself prevented from rotation, it rapidly winds up the strip of material from the object.

I claim:—

15. 1. A device of the class described comprising a revolute shuttle embodying a pair of broken annuli eccentrically mounted with respect to each other, a bobbin-carrier on one annulus and having actuated connection with the other annulus, and a bobbin mounted on said bobbin-carrier.

20. 2. A device of the class described comprising feeding mechanism, a revolute shuttle embodying a pair of broken annuli arranged to revolve around the object carried by said feeding mechanism, a bobbin-carrier mounted on one annulus and having connection with the other, a bobbin mounted on said bobbin-carrier, and means for revolving said annuli simultaneously on different axes.

25. 3. A device of the class described comprising a revolute shuttle embodying a pair of broken annuli revolving on parallel relatively fixed axes offset from each other, a bobbin-carrier on one annulus and means on the other annulus connecting with said carrier for holding it in a relatively fixed position during its orbital movement and a bobbin mounted on said bobbin-carrier.

30. 4. A device of the class described comprising a revolute shuttle embodying a pair of broken annuli revolving on parallel relatively-fixed axes offset from each other, a hinged bobbin-carrier on one annulus, means on the latter having connection with the companion annulus, and a bobbin mounted on said bobbin-carrier.

35. 5. A device of the class described comprising a revolute shuttle embodying a pair of broken annuli revolving on parallel relatively-fixed axes offset from each other, a bobbin-carrier on one annulus, means connecting the two annuli with each other, a bobbin mounted on said bobbin-carrier, and means for simultaneously revolving both annuli in the same direction.

40. 6. A device of the class described comprising a revolute shuttle embodying a pair of broken annuli each of which is eccentrically revolute with respect to the other, a bobbin-carrier positioned in a suitable bearing in one annulus, and means pivotally connecting said bobbin carrier with the other shuttle, a bobbin on said bobbin-car-

rier, and means for simultaneously revolving both annuli in the same direction.

45. 7. A device of the class described comprising a revolute shuttle embodying a pair of broken annuli each eccentrically revolute with respect to the other, a bobbin-carrier positioned in a suitable bearing in one annulus, and means connecting said bobbin-carrier with the other annulus, and means for interlocking said connecting means for preventing the independent rotation of said bobbin.

50. 8. A device of the class described comprising a revolute shuttle embodying broken annuli arranged to revolve on parallel but offset axes of revolution, means for loosely and pivotally connecting said annuli together to insure their simultaneous revolution in the same direction, one annulus provided with a bearing, a shaft positioned in said bearing, means for loosely connecting said shaft with the other annulus, a bobbin mounted on said shaft, and means for revolving said annuli.

55. 9. A device of the class described comprising a revolute shuttle embodying a pair of broken annuli arranged to revolve on parallel but offset axes of revolution, means for loosely and pivotally connecting said annuli to insure their simultaneous revolution, one annulus provided with a bearing, a two part shaft, the two parts of which are hinged together, positioned in said bearing, means for loosely connecting said shaft with the other annulus, a bobbin mounted on said shaft, and means for revolving said shuttle.

60. 10. A device of the class described comprising a revolute shuttle embodying broken annuli the axes of revolution of which are offset from each other, a shaft rotatably mounted on one annulus and constituting a bobbin-carrier, a link pivotally connecting the other annulus and said shaft, means for interlocking said shaft and link for preventing independent rotation of the former, a bobbin mounted on said shaft, and means for revolving said shuttle.

65. 11. A device of the class described comprising a supporting frame, a revolute shuttle embodying broken annuli arranged to revolve on parallel but offset axes of revolution, a series of rollers constituting supporting means for each annulus during its revolution, the rollers supporting one annulus being differently positioned from the rollers supporting the other annulus, one annulus provided with a bobbin-carrier and having pivotal connection with the other annulus and means for simultaneously revolving both annuli.

70. 12. A device of the class described comprising a supporting frame, a series of rollers polygonally positioned on said frame, a broken annulus running on the outer periph-

eries of said rollers, the latter constituting bearings therefor, a second series of rollers on said frame, similarly positioned, a broken annulus mounted on said second series of rollers as bearings, said annuli arranged to revolve on parallel but offset axes of revolution, means for pivotally and loosely connecting said annuli together, a bobbin-carrier on one annulus and having

10 pivotal connection with the other, a bobbin

mounted on said bobbin-carrier, and means for revolving said annuli in unison in the same direction.

In testimony whereof I have hereunto set my hand in presence of two subscribing witnesses.

CURT KUENTZEL.
